ABRADING ELEMENT

Kirke W. Connor, Detroit, Mich., assignor to
 Micromatic Hone Corporation, a corporation
 of Michigan

Application November 11, 1931, Serial No. 574,380

3 Claims. (Cl. 51-280)

My invention relates to abrasive elements and particularly to an abrasive element of the composite type constructed in such manner as to be resilient and containing a lubricant.

5 While my abrasive element will be herein described in relation to its use as an element for a honing tool, it is to be understood that in its broad aspects the abrasive element may be utilized on any dressing machine and especially on machines 10 where rapid grinding, accompanied by high polish, is desired.

The main objects of my invention are; to provide an abrasive element of the composite type which is made up from an abrasive material, a 15 filling material, a lubricant and a bond to form a unit abrasive element; to provide an abrasive element which is resilient and compressible an amount proportional to the cut to be made, the degree of which reduces directly with the compression. To provide a lubricant as a contiguous 20 part of the element to effect its lubrication in the presence of heavy cutting and to effect a high polish as the degree of cut reduces; to provide a lubricant which is preferably a solid such that 25 may be bonded along with the abrasive and filler material, or which may form part of the binder or which may be a fluid and absorbed by the filler or other material, all of which go to make up my composite abrasive element.

30 Other objects and features of novelty of my invention will be either specifically pointed out or will become apparent when referring, for a better understanding of my invention, to the following description in conjunction with the accompanying drawing, wherein:

Figure 1 is a perspective view, in section, of an abrasive element embodying features of my invention.

Fig. 2 is a view similar to that of Fig. 1, showing a modified form which my invention may assume, and

Fig. 3 is a view similar to Figs. 1 and 2, showing a further modified form which my invention may assume.

45 Referring to Fig. 1, the abrasive element 5 is retained in a metal supporting element 6 through the medium of an adhesive material 7 which binds the element to the metal in a well known manner. The abrasive element 5 is constructed of a 50 composition of materials, comprising a body or filler material which is preferably resilient and may be of cork particles, macerated duck or like materials which may have a certain degree of porosity for absorbing and retaining a lubricant such as oil. The cork is bonded with an abrasive mate-

rial which may be carborundum or like well known abradant. The bonding material may be any well known adhesive such as glue, a phenol compound known in the trade as bakelite, a shellac or other suitable substance which preferably has a certain degree of resiliency. In the place of providing a lubricant such as mineral oil which is absorbed by the filler or other material, the lubricant may be a solid, such as graphite or paraffin, or the like, or a combination thereof with the bonding material to form a lubricating binding compound which retains the abrasive material bonded to the filler material.

The composite abrasive element thus formed is resilient and embodies desirable features not present in abrasive elements of the solid type heretofore employed. For example, when the element is employed in a honing tool, the tool may be considerably simplified by having the advancing bias, heretofore provided therein, eliminated and the setting of the tool to provide the proper degree of cut will ensue by adjusting the tool to compress the abrasive element a predetermined amount. After the element has been adjusted in this manner, the initial operation of the elements under compression will effect a rapid cutting of the cylinder wall and as the cutting proceeds the compression of the abrasive element is reduced with a like reduction in the degree of cut effected by the element. As the compression of the honing element decreases the amount of cut in the presence of the lubricant is materially decreased effecting a high polish to the surface. This desirable feature of the flexible abrasive element obtains when the element is employed for grinding surfaces other than the surfaces of cylinder bores.

In Fig. 2, I have illustrated a modified form of abrasive elements which comprises a resilient body member 11 of channel shape having a central groove 12 in which an abrasive material 13 is disposed. The abrasive material may be bonded with a lubricant, the lubricant may be absorbed by the resilient body member 11 or the particles of the body member may be bonded with a solid lubricant. In any case the resulting element is resilient and the benefits derived therefrom, as pointed out in regard to the abrasive element illustrated in Fig. 1, obtains for the structure illustrated in Fig. 2.

A further modified form of the abrasive element is illustrated in Fig. 3 wherein the lubricant 14, the abrasive material 15 and the resilient 45 filler or body members 16 are provided in individual strips and assembled together to effect a

composite element having the resilient features pointed out with regards to the form of the invention illustrated in Figs. 1 and 2.

It is to be understood that other methods and means of assembling the abrasive, the lubricating and the filler materials to form a resilient abrasive element may be utilized such, for example, as providing pads of felt or like material in the form illustrated in Fig. 3 in which a mineral oil or like lubricant may be retained. In a similar manner, the material 11 in Fig. 2 may be the abrading material and the felt pad may be the element 13 disposed therein. Oil may be applied to the pad which will be absorbed and retained for effecting the desired lubrication and a wet type of honing in a dry manner. In any instance, the broad aspect of my invention pertains to the resilient and lubricating features of the composite abrasive element which is submitted to be new in the art.

While I have described and illustrated several embodiments of my invention, it will be apparent

to those skilled in the art that various changes, omissions, additions and substitutions may be made therein without departing from the spirit and scope of my invention, as set forth in the accompanying claims.

5

I claim as my invention:

1. A composite abrading stick including, in combination, a length of abrading material in the nature of a solid stick, and a length of material which will absorb a liquid, one of said lengths being slotted to receive the other.

2. A composite abrading stick including, in combination, a length of abrading material in the nature of a solid stick, and a length of a material containing a lubricant, one of said lengths being slotted to receive the other.

3. A composite abrading stick including, in combination, a length of abrading material in the nature of a solid stick, and a length of lubricating material, one of said lengths being slotted to receive the other.

KIRKE W. CONNOR.
